SANITARY DISCHARGE NOZZLE FOR HOSE

Erich Thomsen, San Francisco, Calif.

Application April 12, 1948, Serial No. 20,567

12 Claims. (Cl. 137—111)

1

The present invention relates to improvements in a sanitary discharge nozzle for a hose, and its principal object is to provide means for protecting the discharge end of the nozzle from contamination by contact with foreign substances.

While my invention may be used for many different purposes, it has been particularly designed for use in connection with a water hose used by railroads for filling the tanks of railroad coaches, dining cars, etc.

These tanks are usually filled from a hydrant disposed a certain distance away from the railroad tracks, by means of a water hose, the free end of which has to be carried back and forth by an attendant for filling operations.

It frequently happens that during the operations the free end of the hose is dragged over the ground surface, or accidentally drops to the ground surface, with the result that foreign, contaminating substances are picked up by the discharge end of the hose and are eventually discharged into the tank along with the water.

In the present invention it is proposed to provide a sanitary discharge nozzle for the hose, the nozzle having protecting means for its discharge end which completely covers the latter at all times except during actual dispensing operations.

It is further proposed to arrange the protecting means in such a manner that it may be easily retracted to clear the discharge end for dispensing operations.

It is further proposed in the present invention to arrange the protecting means in the form of two cylindrical sections forming a complete enclosure about the discharge end of the nozzle, the two sections being hinged so that they may be separated to allow of their retracting movement.

It is a further object of the present invention to provide cooperating means on the nozzle and the cylindrical sections whereby the latter are automatically opened during the retracting movement.

It is further contemplated in the present invention to arrange the opening means for the two cylindrical sections in such a manner that no part thereof will ever contact the discharge end of the nozzle.

And finally, it is proposed to provide a sanitary discharge nozzle of the character described that is very efficient in operation, convenient in use, practically tamper-proof, rugged and simple in construction, and all parts of which may be readily cleaned from the inside by the mere turning on of the water while the parts are in nozzle protecting position.

Further objects and advantages of my invention will appear as the specification proceeds, and the novel features of my invention will be fully defined in the claims attached hereto.

2

The preferred form of my invention is illustrated in the accompanying drawing, in which

Figure 1 shows a side view of my sanitary discharge nozzle, with the protecting elements in closed position,

Figure 2, a longitudinal section through the same,

Figure 3, a side view of the nozzle ready for dispensing operations,

Figure 4, a section taken along line 4—4 of Figure 2, and

Figure 5, a section taken along line 5—5 of Figure 1.

While I have shown only the preferred form of my invention, I wish to have it understood that various changes and modifications may be made within the scope of the claims attached hereto without departing from the spirit of the invention.

Referring to the drawing in detail, my sanitary discharge nozzle comprises in its principal features a pipe section 1 having a pair of cams 2 mounted on opposite sides thereof, a slide 3 mounted on the pipe section and the cams with freedom of retracting and advancing movement, a pair of semi-cylindrical sections 4 having their rear ends pivoted to the slide as at 5 and having shoes 6 mounted for cooperation with the cams 2, a spring 7 on the pipe section urging the slide forward, and springs 8 interconnecting the two cylindrical sections and tending to close the same.

The pipe 1 is preferably straight and threaded at its rear end as at 9 for connection to the end of a water hose. The front end of the pipe section is open and has a suitable discharge end 10 connected thereto which is here shown as a short piece of flexible hose secured to the pipe by means of a clamp 11. This discharge end is intended for insertion through a hole into the tank into which water is to be delivered.

The two cams 2 are disposed on opposite sides of the pipe section and run longitudinally thereof, extending rearwardly up to the threaded section 9. The front ends of the two cams are tapered as at 12, the taper rising gradually for a short distance and then rising abruptly as at 13 to merge into parallel upper and lower faces 14 which extend in parallel relation through the major portion of the length of each cam. A disc 15 is mounted upon the pipe immediately forward of the two cams and serves as a stop for the shoes 6, side portions of the disc being cut away to allow of the passing of the springs 8 on opposite sides thereof.

The slide 3 is in the form of a sleeve having a sliding fit on the pipe section 1 and the side cams 2, and being properly shaped to present material on opposite sides of the cams as at 16.

The sides of the slide have pins 5 projecting radially therefrom, the pins terminating in

handles 17 projecting outwardly, by means of which the slide may be operated.

The two semi-cylindrical sections 4 are provided, at their rear ends, with overlapping ears 18 which are pivoted to the pins 5 and which are adapted to close upon one another to form a complete cylinder when the slide is in an advanced position as shown in Figure 1. The forward ends of the semi-cylindrical sections are closed as at 19 to entirely cover the discharge end 10 as particularly well illustrated in Figure 2; and the two closed ends of the semi-cylindrical sections are somewhat spaced from the discharge end 10 as also shown in Figure 2.

The two semi-cylindrical sections 4 carry, fairly close to their rear ends, the shoes 6 adapted to bear upon the opposite faces of the cams 2. When the slide 3 is in its forward position and the semi-cylindrical sections are closed upon one another to form a complete cylinder, the four shoes 6 rest on the tapered front ends of the cams 2. When the slide 3 is retracted by means of the handles 17, the shoes are made to ride first on the abrupt tapered sections 13 for spreading the two semi-cylindrical sections and then on the parallel faces 14 for maintaining the two semi-cylindrical sections in the same position. When backward pressure on the handles 17 is released, the spring 7 urges the slide 3 forward, allowing the shoes 6 to ride forward on the cams 2 and allowing the semi-cylindrical sections to close, under the influence of the springs 8, when the shoes reach the forward ends of the cams. Further forward movement of the shoes and the slide is arrested by the disc 15.

It will be noted that at the beginning of the retracting movement, when the shoes 6 ride on the tapered section 13, the cylinder comprising the two sections 4 is opened rather abruptly; and this opening movement is calculated to keep the closed front ends of the semi-cylindrical sections out of contact with the front edge of the discharge end 10.

The slide 3 carries a collar 20 at its rear end to serve as an abutment for the spring 7, the other end of the spring bearing on a disc 21 which may be loosely mounted on the pipe section 1 and held in place by the hose coupling.

The operation of my invention will be readily understood from the foregoing description. The spring 7 normally urges the slide 3 and the cylinder forward so as to close the semi-cylindrical sections 4 upon the discharge end 10 in the manner illustrated in Figure 2. In this position the discharge end of the nozzle is completely enclosed and there is no possibility of its coming in contact with contaminating surfaces even if it is dragged over the ground surface. The shoes 6, in this position, bear on opposing faces of the extreme forward ends of the cams 2.

As the operator is ready to insert the discharge end 10 through a hole in the tank to be filled, he retracts the slide 3 by means of the handles 17, with the result that the shoes 6 bearing on the cam faces 13 immediately spread the semi-cylindrical sections 4 so as to clear the discharge end 10 which may now be inserted. As the dispensing operation is finished, the operator merely withdraws the discharge end 10 from the tank whereupon the spring 7 will automatically push the slide 3 and the cylindrical sections forward, and as soon as the shoes 6 reach the forward ends of the cams 2, the cylindrical sections are automatically closed upon one another by means of the springs 8.

During the dispensing operations the slide may be easily held in its rearward position by merely pressing the front ends of the semi-cylindrical sections against the margin of the hole through which the discharge end 10 is projected. The closing action, upon release, takes place immediately and is sufficiently fast to close the cylinder upon the discharge end 10 before the latter would reach the ground surface even in case of an accidental dropping of the nozzle.

The nozzle can be cleaned very quickly by causing the water to run with the cylinder in closed position, in which case the water will force out any contaminating matter that may have collected in the crevices.

I claim:

1. A sanitary discharge nozzle for a hose, comprising a pipe section adapted for securing upon the hose, a discharge end for the pipe section, a slide retractable on the pipe section, a longitudinally split cylinder pivoted upon the slide with freedom of opening and closing movements and shaped to enclose the discharge end when the slide is in advanced position, and cooperative means on the pipe section and the cylinder for opening the latter when the slide is retracted on the pipe section.

2. A sanitary discharge nozzle for a hose, comprising a pipe section adapted for securing upon the hose, a discharge end for the pipe section, a slide retractable on the pipe section, a longitudinally split cylinder pivoted upon the slide with freedom of opening and closing movements and shaped to enclose the discharge end when the slide is in advanced position, and cooperative means on the pipe section and the cylinder for opening the latter when the slide is retracted on the pipe section, the latter means being operable to maintain clearance between the cylinder and the discharge end during the opening movement.

3. A sanitary discharge nozzle for a hose, comprising a pipe section adapted for securing upon the hose, a discharge end for the pipe section, a slide retractable on the pipe section, a longitudinally split cylinder pivoted upon the slide with freedom of opening and closing movements and shaped to enclose the discharge end when the slide is in advanced position, and cooperative means on the pipe section and the cylinder for opening the latter when the slide is retracted on the pipe section, the latter means comprising a cam mounted on the pipe section longitudinally and shoes mounted on the cylinder sections and riding on opposite faces of the cam.

4. A sanitary discharge nozzle for a hose, comprising a pipe section adapted for securing upon the hose, a discharge end for the pipe section, a slide retractable on the pipe section, a longitudinally split cylinder pivoted upon the slide with freedom of opening and closing movements and shaped to enclose the discharge end when the slide is in advanced position, and cooperative means on the pipe section and the cylinder for opening the latter when the slide is retracted on the pipe section, the latter means comprising a pair of cams mounted longitudinally on the pipe section and shoes mounted on the cylinder sections and riding on opposite faces of the cams.

5. A sanitary discharge nozzle for a hose, comprising a pipe section adapted for securing upon the hose, a discharge end for the pipe section, a slide retractable on the pipe section, a longitudinally split cylinder pivoted upon the slide with freedom of opening and closing movements and shaped to enclose the discharge end when the

slide is in advanced position, and cooperative means on the pipe section and the cylinder for opening the latter when the slide is retracted on the pipe section, the cylinder having means for normally closing the same and the slide having means normally urging the same into advanced position.

6. A sanitary discharge nozzle for a hose, comprising a pipe section adapted for securing upon the hose, a discharge end for the pipe section, a slide retractable on the pipe section, a longitudinally split cylinder pivoted upon the slide with freedom of opening and closing movements and shaped to enclose the discharge end when the slide is in advanced position, and cooperative means on the pipe section and the cylinder for opening the latter when the slide is retracted on the pipe section, the latter means comprising a pair of cams mounted longitudinally on the pipe section and shoes mounted on the cylinder sections and riding on opposite faces of the cams, and the cams being shaped to abruptly open the cylinder at the beginning of the retracting movement so as to maintain clearance between the cylinder and the discharge end.

7. In a sanitary discharge nozzle of the character described, a pipe section having longitudinal cams on opposite sides thereof, a slide retractable on the pipe section and the cams, a split cylinder having two semi-cylindrical sections with their rear ends pivoted to the slide for opening and closing movements, and shoes on the cylinder sections cooperable with the cams for opening the cylinder when the slide is retracted.

8. In a sanitary discharge nozzle of the character described, a pipe section having longitudinal cams on opposite sides thereof, a slide retractable on the pipe section and the cams, a split cylinder having two semi-cylindrical sections with their rear ends pivoted to the slide for opening and closing movements, and shoes on the cylinder sections cooperable with the cams for opening the cylinder when the slide is retracted, the cylinder sections having closed ends to form a complete enclosure when the cylinder is closed.

9. In a sanitary discharge nozzle of the character described, a pipe section having longitudinal cams on opposite sides thereof, the cams having parallel upper and lower faces through the major portions of their lengths and being tapered in their front ends, a slide retractable on the pipe section and shaped for riding upon the major cam portions, a split cylinder having two semi-cylindrical sections with their rear ends pivoted

to the slide for opening and closing movements, and shoes on the cylindrical sections cooperable with the front ends of the cams for opening the cylinder upon initial retracting movement and cooperable with the major portions of the cams for maintaining the cylinder open as the retracting movement is continued.

10. In a sanitary discharge nozzle of the character described, a nozzle having a discharge end, and a cylinder mounted upon the nozzle to form a complete enclosure for the discharge end, the cylinder being split longitudinally to present two semi-cylindrical sections having their rear ends pivoted with respect to the nozzle for opening and closing movement, and the cylinder being retractable upon the nozzle to clear the discharge end for dispensing operations.

11. In a sanitary nozzle of the character described, a nozzle having a discharge end, a cylinder retractable on the nozzle and shaped to normally form a complete enclosure for the discharge end, the cylinder being split longitudinally to present two semi-cylindrical sections pivoted at their rear ends for opening and closing movements, and cooperative means on the cylinder sections and the nozzle for automatically opening the cylinder when it is retracted.

12. In a sanitary nozzle of the character described, a nozzle having a discharge end, a cylinder retractable on the nozzle and shaped to normally form a complete enclosure for the discharge end, the cylinder being split longitudinally to present two semi-cylindrical sections pivoted at their rear ends for opening and closing movements, and cooperative means on the cylinder sections and the nozzle for automatically opening the cylinder when it is retracted, with means normally urging the cylinder into advanced position and means normally tending to close the cylinder.
